UNITED STATES PATENT OFFICE

JERRY S. WALKER, OF SEMINOLE, OKLAHOMA, ASSIGNOR OF FIVE FORTY-EIGHTHS TO JAMES B. ALLEN, ONE-TWELFTH TO CLAUD A. WILSON, ONE-TWELFTH TO EMMETT C. WILSON, ONE-TWELFTH TO EDD T. MAYES, ONE-TWELFTH TO EDWARD C. KELLEY, ONE TWENTY-FOURTH TO SAMUEL S. GREEN, AND ONE FORTY-EIGHTH TO TED MORGAN, ALL OF SEMINOLE, OKLAHOMA

AEROPLANE

Application filed December 18, 1928. Serial No. 326,799.

The present invention relates to aircraft of the heavier than air type, and the primary object of the invention is to provide a construction for aeroplanes which will greatly reduce the dangers encountered thru forced landings caused by engine or any other troubles which would act to cause the plane to descend.

A further object of the invention is to provide an aeroplane having such control as to permit of the aeroplane being lowered in a comparatively vertical direction and on an even keel or upright position with little or practically no forward motion to the plane.

A further object of the invention is to provide an aeroplane of such construction as to permit of quick raising of the aeroplane from the ground without requiring the usual long run ordinarily required for a "take off."

A further object of the invention resides in a construction wherein the tail acts in conjunction with the wings of the aeroplane for sustaining the weight of the plane and also as a stabilizing means.

A still further object of the invention is to provide an aeroplane having companion sets of tiltable wings arranged in tandem and connected for unitary or independent movement for enabling the aeroplane to descend substantially vertically and without rolling.

Other objects and advantages of the invention will be apparent during the course of the following detailed description, taken in connection with the accompanying drawings forming a part of this specification and in which drawings:

Figure 1 is a top plan view of the improved aeroplane.

Figure 2 is an enlarged central longitudinal section thru the body or fuselage of the aeroplane and showing the controls and one manner of propelling the aeroplane.

Figure 3 is a fragmentary side elevation and showing by dotted lines the manner in

which the wings may be tilted or inclined to produce more lift.

Figure 4 is an enlarged fragmentary detail section taken substantially on the line 4-4 of Figure 2 and showing the manner in which the companion sets of wings are detachably secured to the sides of the aeroplane body.

Figure 5 is an enlarged detail view of the wing mountings and also showing the spring sleeve connecting companion sets of wings to permit independent tilting of the wings.

Figure 6 is an enlarged fragmentary view of one of the wing control levers and showing one method of retaining the keeper dog unlatched to permit free swinging of the lever.

Figure 7 is an enlarged fragmentary view of the foot control pedal for the tail or sustaining rudder.

Figure 8 is an enlarged fragmentary section on line 8-8 of Figure 4 and showing the manner in which the wing braces are connected to permit tilting of the wings.

Referring to the drawings in detail, and wherein similar reference characters designate corresponding parts thruout the several views, the numeral 5 designates the body or fuselage provided with fore and aft sets of laterally projecting wings 6 and 7 respectively, and a horizontally disposed sustaining tail 8 of a substantial area as clearly shown in Figure 1.

The body or fuselage 5 embodies a suitably covered framing including a pair of upper longitudinal side rails 9 which preferably extend in parallel relation. The top, bottom and sides converge at their forward ends to provide a pointed forward end 10 for the fuselage, while the rear end of the fuselage also converges to a point with the bottom rounded as at 11. A suitable seat 12 is mounted in the fuselage beneath the cockpit opening 13. The landing gear for the aeroplane preferably consists of a pair of front

wheels 14 mounted one at each side of the fuselage, and a single rear wheel 15 suitably mounted adjacent the rear end of the fuselage at the longitudinal center thereof. The 5 wheels 14 and 15 may be mounted in any suitable shock absorbing means and are preferably provided respectively with brake drums 14' and 15' housing suitable brake mechanisms controlled by a brake pedal 16. 10 The brake rod 17 connects the pedal 16 with the front wheel brake, while a brake rod 18 connects the pedal 16 with the brake for the rear wheel, and suitable means such as a spring 19 may be associated with the brake 15 rod 17 for causing a braking action to be created on the brake drum 15' slightly in advance of the braking action on the brake drum 14'. 15

Referring now to the specific wing arrangement and manner of mounting and operating the same, each of the four wings are adapted for detachable mounting at the sides of the fuselage 5 within identical types of mountings supported on the longitudinal 20 frame rails 9. The wings are of substantially rectangular shape in plan and are preferably provided with cambered upper surfaces and flat lower surfaces as shown in Figure 3, and the wings are intended to be mounted in tandem with the trailing edges of the fore set of wings spaced in advance of the leading edges of the aft or rear set of wings 7. 25

Referring particularly to Figures 4 and 5 wherein is shown in detail the mounting arrangement for the sets of wings, it will be noted that the companion sets of aft wings 7 are mounted in bearing brackets 20 mounted in axial alignment beneath the side frame rails 9. Rotatably mounted in each bearing bracket 20 is a flanged bearing 21 provided with a thru and thru square and tapering opening 22. These openings 22 are intended to receive square and tapering shanks 23 of wing supports 24 which are rigidly attached in any preferred manner to the inner ends of the wings. The inner ends of the shanks 23 are reduced and threaded as at 25 to receive suitable nuts 26 serving to retain the wing supports coupled to the flanged bearings. 30 Preferably cast integral at the inner side of the bearings 21 is a cupped portion 27 provided with a square extension 28 extending co-axial with the axis of rotation of the bearing portion 21. The cupped portion 27 as will be observed permits of ready replacing and removal of the retaining nuts 26. Depending from and if so desired, formed integral with the bearings 21 is a crank arm 29 which when swung in a direction longitudinally of the fuselage acts to tilt or rock their respective wings about an axis at a right angle to the longitudinal axis of the fuselage. It may here be well to note that the wing supports or fixtures 24 are disposed slightly forward of the longitudinal axis of the wings. 35

Connected between the square extensions 28 of each fore and aft set of axially aligned wing mounting bearings 21 is a longitudinally split tubular tie member 30 having squared hollow end portions 31 for receiving the square extensions 28 and to be attached thereto as by suitable fastening elements 32. These tie members 30 are preferably formed from spring steel and while normally acting to retain their companion sets of wings in a like position will permit of independent rocking of companion wings thru a twisting of the tie member. As will be observed, the spring tie member 30 aside from permitting independent tilting of the wings, also acts as a brace or tie between the companion sets of wings. 70

As to the operating means for tilting the wings, the same will permit, thru the spring tie members 30, a pair of wings 6 and 7 at 80 one side of the fuselage to be tilted while the pair of wings 6 and 7 at the opposite side of the fuselage may be held horizontal or at a tilted position. This control means consists of a pair of pivoted wing control levers 90 34 arranged one at each side of the fuselage directly forward of the seat 12 with each lever having connected thereto a forwardly extending front wing control rod 35 and a rearwardly extending rear wing control rod 36, 95 the rods 35 and 36 being pivotally connected to their respective control levers. The forwardly extending control rods 35 are pivotally connected at their forward ends to the lower ends of the crank arms 29 for operating the front wings, while the rear ends of the control rods 36 are pivotally connected to the lower ends of the crank arms 29 for operating the rear set of wings. As will be observed in Figure 2 when the control lever 34 is swung forwardly the crank arms 29 will also be swung forwardly and cause the forward or leading edges of the wings to be tilted upwardly as shown by dotted lines in Figure 3. When the lever is swung rearwardly the tilting of the wings will be reversed, that is, the leading edges of the wings will be lowered. Each control lever 34 is provided with a toothed sector 37 in which a keeper engages for retaining the lever in any set position. The keeper is operated by a pivoted hand grip 38 as shown in Figure 6, and this pivoted hand grip when released carries a latch 39 which so engages in the upper end of the lever 34 as to retain the keeper out of engagement with the toothed sector 37 so that the lever may swing free when so desired. When either one of the wing control levers 34 is in an unlatched position the operator may control both sets of wings by one control lever. When the keeper of either lever is in engagement with the sector 37 the wings as will be observed, at one side of the fuselage will be held in a set position and the pair of wings at the oppo- 100 105 110 115 120 125 130

site side of the fuselage allowed to be rocked thru the provision of the spring tie members 30.

5 A means is provided for limiting tilting or rocking of the wings, and this means may consist of arcuately slotted guide members 40 suitably secured to the sides of the fuselage 5 adjacent the front and rear edges of each wing. The arcuate slots in the guide members 40 are closed at both ends and receive suitable pins or projections 41 carried by the inner ends of the wings adjacent the front and rear edges of the wings. The slots in the members 40 are on an arc concentric with the pivotal axis of the wings and as the pins or projections 41 reach the ends of the slots further tilting or rocking of the wings will be prevented.

10 Projecting upwardly from the fuselage above each point of mounting of the wings, is a brace 42, with each transversely aligning set of braces having a guy wire 43 trained thereover and connected at opposite ends to pivoted anchors 44 mounted in the wings. These guy or brace wires 43 serve to brace the sets of pivoted wings, and connected with the lower end of each pivoted anchor 44 is a lower guy wire 45 which extends to the lower edge of the fuselage 5. The anchors 44 extend vertically thru the wings and are pivotally mounted upon a suitable bracket 46 carried by the wing structure, with the pivot pin for the anchor arranged in axial alignment with the pivotal axis of the wings. This manner of supporting the wings will allow for tilting of the wings without creating any binding action upon the guy wires 43 and 45.

15 Referring now to the tail 8, which acts to aid in sustaining the aeroplane and also balancing the same, the same as will be observed is of relatively large area and is pivotally mounted at its forward edge as at 47. The tail 8 is intended to be lowered by means of a cable 48 connected with a foot pedal 49 shown in detail in Figure 7 operating in conjunction with a toothed rack 50. The operation of the foot lever 49 is such as to permit of the tail or horizontal rudder 8 being retained in a set position. The lever 49 is provided with a tooth 51 for engaging in the notches of the rack 50, and connected with the lower end of the lever is a spring 52 mounted upon a suitable block 53 rotatable in a bearing 54. When desiring to free the lever the operator merely shifts the lever laterally as shown by dotted lines in Figure 7 and then swings the lever forwardly or rearwardly to the desired position. A hand lever 55 is provided for elevating the tail or sustaining rudder 8, and a cable 56 is connected with the lever and trained over suitable sheaves for proper connection with the tail. Suitable leaf springs 57 act upon opposite sides of the lever 55 for normally re-

taining the same in an upright position for normally returning the lever to an upright position when the tail or sustaining rudder 8 is horizontal. This hand lever 55 will ordinarily only be required for use in righting the plane or when it is desirable to forcibly swing the tail away from the fuselage.

20 Referring now to the propelling means for the aeroplane, a pedaled drive means has been shown by way of example, altho it is to be understood that any suitable motive power may be employed. In the example shown the drive means consists of a power gear 60 rotatable by suitable pedals 61, and which power gear meshes with a small bevel gear 62 connected with a drive shaft 63 extending longitudinally of the fuselage and carrying at its rear end a bevel gear 64 meshing with a bevel gear 65 carried by a transverse fly wheel shaft 66 on which are mounted suitable fly wheels 67. This transverse driven shaft 66 preferably extends at its ends slightly beyond the side walls of the fuselage and has detachably coupled to its ends as by means of suitable couplings 68, one end of flexible drive shafts 69 extending outwardly and upwardly beneath the aft or rear set of wings 7. Mounted in each aft wing 7 is a propeller shaft 70 which projects forwardly of the wing and carries suitable propellers 71. Each shaft 70 carries a worm 72 which meshes with a worm gear 73 driven by the flexible drive shaft 69. The gearings 70 and 73 are preferably enclosed in the wing constructions and the outer ends of the flexible drive shafts 69 are preferably coupled with a detachable connection 74 to stub shafts of the worm gears projecting downwardly thru the wings. Any suitable type of clutch device as at 75 in Figure 2 may be interposed in the drive shaft 63 or at any other desired location for permitting continued rotation of the fly wheel shaft 66 under its attained momentum without rotation of the power gear 60.

25 As will be observed, the propellers 71 are carried by the leading edges of the rear set of pivoted wings 7 and are intended for up and down movement upon tilting of the wings so that the axis of rotation of the propellers inclines with the angular inclined position of the wings. By observing Figure 3 it will be seen that when the wings 7 are inclined as shown in the dotted line position that the propellers 71 are in a position to produce both a lifting and propelling force which will tend to raise the aeroplane with a quick action. During flight, the movement of the aeroplane may be controlled almost entirely thru proper tilting of the wings and the tail or sustaining rudder remain in substantially a set position. By so having the pairs of wings at either side of the fuselage connected so that the same may be tilted independently of the wings at the opposite side of the fuselage, it will be seen that thru tilting of one

pair of wings that one side of the aeroplane will be elevated thru the additional lift acting beneath the tilted wings. In making a substantially vertical descent, it will be seen that by proper tilting of the wings at either side of the fuselage that more or less slip will be caused at the tilted wing side and cause that side to lower slightly faster than the wings in the flat position at the opposite side of the fuselage until the aeroplane has been brought to a level keel. Should the forward end of the fuselage have a tendency to lower too rapidly, the fuselage may be brought to a horizontal position thru proper operation of the sustaining rudder or tail 8.

The outer ends of the sets of wings are preferably connected by suitable tie members 80 pivotally connected to the ends of the wings at their pivotal axes.

20 While the aeroplane has been shown provided with a manually operable propelling means, it is to be understood that any type of power drive means may be substituted and arranged in the fuselage at a location to properly balance. It is preferred however that when power drive means be employed that the propellers be carried by the leading edges of the front set of wings owing to the increased power which will be delivered by the 30 propellers.

From the foregoing description it will be apparent that a novel and improved construction for aeroplanes has been provided which will permit of landing and take offs 35 of the aeroplane upon relatively small ground areas. It will also be apparent that a novel wing control arrangement has been provided wherein the wings may be so operated as to retain the aeroplane on an even keel and 40 against rolling. It will further be apparent that a novel arrangement has been provided wherein the tail acts as a sustaining means for the aeroplane in conjunction with the pivotally mounted wings.

45 Changes in detail may be made to the form of invention herein shown and described, without departing from the spirit of the invention or the scope of the following claims.

I claim:

50 1. An aeroplane comprising a body having pointed front and rear ends, sets of wings mounted in tandem to project laterally from opposite sides of the body, said wings being pivotally mounted to tilt about an axis transversely of the body, and a relatively large sustaining tail pivotally mounted above the rear end portion of the body.

2. In an aeroplane, a body, a pair of wings pivotally mounted in tandem at one side of 60 the body, a companion pair of wings pivotally mounted in tandem at the opposite side of the body on pivots co-axial with the first mentioned pair of wings, a propeller mounted at the leading edge of the rear wing of each 65 pair of wings, independently operable con-

trol means for correspondingly moving the wings of each pair of wings, a sustaining rudder hingedly carried by the body rearwardly of the wings, and control means for the rudder.

3. In an aeroplane, a body, pairs of wings pivotally mounted at opposite sides of the body, means for tilting the wings at one side of the body independently of the wings at the opposite sides of the body, a sustaining 70 rudder hingedly mounted at its forward edge to the body rearwardly of said wings, a foot pedal for lowering the rudder and capable of being locked in set positions, a lever for raising the rudder, and spring means acting upon 80 the lever for normally returning the lever to a set position.

4. In an aeroplane, a body, a set of fore and aft wings pivotally and detachably mounted upon the body, control means for independently pivoting the wings in unison at either side of the body, drive means including a shaft extending transversely of the body, a shaft mounted in each wing of one set of wings, a propeller mounted upon each shaft 90 at the leading edge of each wing, a driving connection detachably connected between each propeller shaft and the ends of the power driven shaft, and a sustaining rudder mounted horizontally upon the body rearwardly of said wings. 95

5. In an aeroplane, a pair of wings pivotally and detachably mounted in tandem at opposite sides of the body, means for tilting either pair of wings independently of 100 the companion pair, bracing for the wings including an anchor pivotally carried by each wing on its axis of rotation and guy wires connected with the anchors above and below the wings, means for propelling the aeroplane, and a horizontally hinged tail of relatively large area mounted on the body rearwardly of the wings. 105

6. In an aeroplane, a body, a pair of wings pivotally mounted in tandem at each side of 110 the body with the pivotal axes of the wings of each pair aligning transversely of the body, a control lever for each pair of wings, releasable latch means for each lever, and a spring shaft connecting axially aligning 115 wings.

7. In an aeroplane, a body, a set of front and rear bearing brackets mounted in the body, a mounting bearing rotatably mounted in each bracket and each including a crank arm, a wing non-rotatably mounted in each bearing to project laterally of the body, a spring shaft connecting the mounting bearings in axial alignment, a pair of control levers each having latch means for releasably retaining the levers in a set position, and control rods connected between each lever and the crank arms to permit tilting of the wings at either side of the body in a like direction. 120 125 130

8. In an aeroplane, a body, bearing brackets mounted in axial alignment transversely of the body, a mounting bearing rotatably mounted in each bracket and including an inward extension axially with the axis of rotation of the bearing, a spring shaft connected between the extension to permit relative rotation of the mounting bearings, means connected with each mounting bearing for rotation thereof, and a wing non-rotatably supported in each mounting bearing.
